UNITED STATES PATENT OFFICE

BERT C. BERRY, OF MOLINE, ILLINOIS

DESIGN FOR A CORN SERVING DISH

Application filed January 2, 1931. Serial No. 38,177. Term of patent 14 years.

To all whom it may concern:

Be it known that I, BERT C. BERRY, a subject of the King of Great Britain, having declared my intention of becoming a citizen of the United States, and residing at Moline, in the county of Rock Island and State of Illinois, have invented a new, original, and ornamental Design for a Corn Serving Dish, of which the following is a specification, reference being had to the accompanying drawings, forming part of this specification.

In the drawings:

Fig. 2 is a side elevation of the dish; and

Fig. 3 is an end elevation thereof.

I claim:

The ornamental design for a corn serving dish as shown.

BERT C. BERRY.
